UNITED STATES PATENT OFFICE.

CHARLES N. MOORE, OF NEWHALL, CALIFORNIA.

ORE GRINDER AND AMALGAMATOR.

SPECIFICATION forming part of Letters Patent No. 521,663, dated June 19, 1894.

Application filed October 30, 1893. Serial No. 489,524. (No model.)

To all whom it may concern:

Be it known that I, CHARLES N. MOORE, a citizen of the United States, residing at Newhall, Los Angeles county, State of California, have invented an Improvement in Ore Grinders and Amalgamators; and I hereby declare the following to be a full, clear, and exact description of the same.

My invention relates to an apparatus for grinding and amalgamating ores or rock containing precious metals.

It consists in certain details of construction which will be more fully explained by reference to the accompanying drawings, in which—

15 Figure 1 is a vertical section of my apparatus. Fig. 2 shows a driving mechanism.

A is a base of sufficient area fixed upon a suitable support and having a vertical cylindrical extension A' in the center. Around 20 this vertical extension fits the bored out central portion of the pan B, the bottom of which declines from the center to the rim or periphery which stands at a slight outward angle as shown.

25 Upon the bottom of the pan B are placed dies C suitably constructed and fitted to cover the bottom of the pan, and receive the wear caused by the grinding. These dies are removable for the purpose of cleaning, or to replace when worn out.

In the center of the standard A' is fixed a stem or spindle E which projects vertically upward, and forms the shaft around which the central hub of the spur gear D is fitted to 35 turn.

Upon the top of the hub, and forming a part of it, is the feeding hopper D', the center of which is in the form of a cone, declining outwardly to its junction with the bottom 40 of the hopper sides. At this point openings a are made through which the ore may be delivered upon the surface of the dies C within the pan B. Around the periphery of the lower part of the pan B openings are made 45 which are covered with wire screen cloth d, and exterior to the pan is fitted the circular copper amalgamated trough c which is adapted to receive the pulp as it is discharged through the screens d, and within this trough 50 any valuable metallic particles are amalgamated and saved. This annular trough has a

discharge opening or chute upon one side for the escape of the lighter, worthless particles.

In order to properly grind and pulverize the ore which falls into the pan from the hopper, 55 I employ the rollers F which are in form of frustums of cones, the angle of the conical sides being such that when the side rests upon the dies C in the bottom of the pan, a shaft extending centrally through the conical rollers will be approximately horizontal. These shafts G have their inner and outer ends respectively journaled in boxes H which are let into the lower part of the hub, and of the periphery respectively, of the gear wheel D. 65

The pan B is caused to rotate in one direction, while the rollers F, traveling upon its bottom, are rotated with relation to the pan, by means of the following mechanism: I I are horizontal shafts journaled upon suitable 70 supports extending radially outward beneath the bottom of the pan B, and having fixed to them the beveled driving pinions K K. Upon these shafts are anti-friction rollers J, upon which a downwardly projecting flange from 75 the bottom of the pan is adapted to travel. The beveled pinions K on the shafts I are adapted to mesh with corresponding teeth upon the bottom of the pan B exterior to the anti-friction supporting wheels J, so that by 80 the rotation of the shafts I I the pan will be driven in one direction. As there are two of these shafts upon opposite sides of the pan, it will be manifest that they must be driven in opposite directions. Power to drive these 85 shafts I is derived from a driving countershaft L having upon it a sprocket-wheel M, and a chain N passes around this sprocket-wheel, and a corresponding sprocket-wheel M' which is fixed directly to the shaft I upon one 90 side of the pan, while upon the opposite side, a corresponding chain passes around a sprocket-wheel, the shaft of which carries a spur gear, and this gear meshes with a corresponding gear upon the shaft I upon that 95 side, so that by means of the intermediate gear, the motion of this shaft is reversed from that of the shaft upon the opposite side, both shafts thus acting to drive the pan in one direction. 100

In order to rotate the gear-wheel D, and with it the conical crushing rollers F whose

shafts are journaled in the gear-wheel, as before described, I have shown vertical shafts O journaled in boxes P having keyed upon the upper end, driving pinions Q, the teeth 5 of which engage with the teeth of the gear D and rotate it oppositely to the pan B. These vertical shafts O have fixed upon them the beveled pinions R, and these pinions are engaged by the bevel-wheels S which are fixed 10 to the horizontal shafts I, so that when the horizontal shafts I are driven as previously described, they will transmit motion to the pan B, and through the bevel gears R and S, and the shafts O to the pinions Q, and thence 15 to the spur gear D which carries the grinding rollers F.

The whole mechanism is easily separated by lifting the spur gear D with the hopper and grinding rollers from the pan, after which 20 the pan may be lifted, the dies removed, cleaned and replaced, the trough c cleansed of amalgam, and the whole replaced again ready for work.

Having thus described my invention, what 25 I claim as new, and desire to secure by Letters Patent, is—

1. A grinding pan having the inclined bottom, a fixed central post with a standard about which the center of the pan is fitted to receive, horizontal shafts extending outwardly from beneath the bottom of the pan, anti-friction rollers upon said shafts, and flanges upon the bottom of the pan adapted to travel upon said rollers, a toothed gear surrounding the 35 bottom of the pan, pinions upon the horizontal shafts engaging said gear, and mechanism whereby the shafts are driven so as to transmit motion to the pan, together with grinding shoes or rollers movable over the bottom 40 of the pan, the horizontal gear wheel above and of greater diameter than said pan and having bearings in which said shoes or rollers are mounted, and gearing connecting said horizontal shafts with said roller carrying 45 gear wheel substantially as herein described.
2. A grinding pan having the inclined bottom, dies fixed therein, a central base and standard about which the center of the pan is fitted to rotate, radial shafts extending outwardly beneath the bottom of the pan, anti-friction rollers upon said shafts by which the 50 pan is supported, a gear around the periphery of the bottom of the pan and pinions upon the shafts adapted to engage the gear, sprocket 55 wheels fixed upon the shafts and receiving power by chains from other sprocket-wheels fixed upon a driving counter-shaft, conical rollers having horizontal shafts journaled in a gear-wheel turning loosely above the top of 60 the pan and intermediate gears whereby motion is transmitted to drive said gear and the crushing rollers with relation to the pan, substantially as herein described.
3. A grinding pan having the inclined bot-

tom and dies, radial shafts with supporting 65 anti-friction rollers upon which the pan rests, pinions upon the shafts and a gear upon the pan bottom through which motion is transmitted to rotate the pan, a central base and standard about which the center of the pan 70 is fitted to rotate, a fixed spindle extending upwardly from the standard, a gear of larger diameter than that of the pan having a central hub fitted to rotate upon the spindle, conical rollers, the shafts of which are journaled in boxes in the hub and rim of the gear, so that the rollers travel upon the dies on the pan bottom, vertical shafts having spur pinions adapted to engage the gear, and bevel gears upon said shafts and upon the main 80 driving shafts whereby motion is communicated to rotate the gear and the crushing rollers simultaneously with the movement of the pan, substantially as herein described.

4. A grinding pan having the conical bottom and die mechanism by which a rotary motion is imparted to the pan about a central base and standard, a vertical spindle extending upward from the standard, a spur gear of larger diameter than that of the pan, 90 intermediate gears whereby motion is transmitted from the main driving shafts to rotate the pan and the gear, crushing rollers, the peripheries of which fit the bottom of the pan, and the shafts of which are journaled so as 95 to be driven by the gear, a hopper extending upwardly from the hub of the gear having a conical bottom, and discharge openings around the periphery through which ore is delivered between the crushing rollers and the bottom 100 of the pan, substantially as herein described.

5. A grinding pan having the inclined bottom and dies fitted thereon, conical rollers with horizontal shafts a horizontal gear-wheel having the same axis of rotation as the pan, 105 and journal-boxes in which the shafts of the grinding rollers are carried, a central conical hopper adapted to deliver ore around its periphery between the grinding rollers and the bottom of the pan, horizontal radial shafts 110 with pinions engaging a gear upon the bottom of the pan, and vertical shafts with gears engaging the periphery of the gear which carries the crushing rollers, intermediate gears and pinions whereby the vertical shafts are 115 driven and the pan and crushing rollers rotated simultaneously, openings with screens fitted around the bottom and outer periphery of the pan, and a surrounding amalgamated copper trough into which the pulp is discharged through the screens, substantially as 120 herein described.

In witness whereof I have hereunto set my hand.

CHARLES N. MOORE.
